UNITED STATES PATENT OFFICE.

MICHAEL KIRSCH, OF MILWAUKEE, WISCONSIN.

MULTIPLE-UNIT SINGLE-CONTROL EXTENSION STAGING.

Application filed June 30, 1927. Serial No. 202,662.

My invention relates to multiple unit extension staging.

The objects of my invention are to provide a series of supporting units for staging 5 adapted to be individually or collectively adjusted in height from a single manual control. More particularly stated, the object of my invention is to provide a series of like extensible staging units each provided with 10 a mechanism for individually adjusting the particular staging unit and provided with communicating motion transmitting connections for simultaneous adjustment of the entire series.

15 In the drawings:

Figure 1 is a fragmental front elevation showing two units of a series of staging supports equipped with my invention.

Figure 2 is a side view of one of my staging units showing my drum and cable mechanism for intercontrol of my staging units.

Figure 3 is a detail plan view of the drum and clutch mechanism and slide in each of my staging units.

25 Figure 4 is a section on line 4—4 of Figure 3.

Figure 5 is a detail of a part of the throw-out mechanism for my drum control.

Like parts are identified by the same reference characters throughout the several views.

Each of my staging units comprises fundamentally the well-known form of extension ladder consisting of a main ladder 1 and its extension 2 slidably mounted upon 35 one another. A bar 3 comprises a retaining member and the clamp 4 secured at either end thereof forms a pivotal connection at 5 for adjustable braces 6 which extend as 40 shown in Figure 1 from the top of one ladder to the bottom of another ladder comprising the next unit of the series control which is the essence of my invention. The extension 2 of each unit of the series may be 45 used to support the usual staging planks 7 upon the bracket 8 secured to rungs 9 of the extension.

A pulley 10 mounted upon the bar 3 receives the cable 11 which is adapted to raise 50 and lower the extension under the control of the drum and clutch mechanism now to be described.

At a convenient height for manual operation is provided a frame work 20 near the 55 base of each of the main ladders 1. Within this frame work and mounted in a horizontal

position at right angles to the rungs 9 of the ladders is a pair of drums 25 and 26 upon shaft 27 rotatable in bearings 21 and 22, the drum 25 being splined to the shaft 27 and drum 26 being mounted for free rotation thereon. Drum 25 is mounted on the shaft 27 for limited reciprocation axially of the shaft to the end that the drum 25 may be moved rearwardly in the direction of drum 26 and cause dogs 28 and 29 which are integral with drums 25 and 26 respectively to engage one another, with the result that rotation of the shaft 27 and the drums 25 will alternatively turn the drum 26 or leave it 70 free for rotation on shaft 27 accordingly as the drum 25 is moved rearwardly or forwardly at the will of the operator. Collars 30 secured tightly to shaft 27 by means of set screws 31, or otherwise, limit the forward 75 or rearward movement of the shaft 27 as indicated in Figure 3. The lever 32 may be pivotally positioned upon its mounting 33 to provide manual control of the drum 25. A rack 35 and pawl 36 construction is provided 80 as shown in Fig. 3 to prevent motion of the drum 26 at times when the clutch dogs 28 and 29 are in disengaged position. Motion transmitting links 37 and 38 may be provided to immediately engage the pawl 36 85 with the rack 35 automatically when the drum 25 is disengaged from the drum 26. A crank 34 is provided for manual rotation of the shaft 27.

For operation of a series of staging units 90 each of which is provided with the drum mechanism above described I have provided for the winding of cable 11 upon drum 25 and I have provided a cable 40 to be wound a number of times around each of the drums 95 26 successively throughout the series of staging units used in accordance with my invention. The operation of the staging controlled by these cables will thereafter be as follows.

When the units of my staging system are 100 finally placed in position in connection with a building wall such as that shown at 45 any regularities in the ground or supporting material at 50 may be compensated for by individual adjustment of each staging unit extension 2 by throwing the lever 32 backward thereby releasing the clutch dogs 28 and 29 from engagement with one another. Rotation of the shaft 27 by means of the 105 crank 34 will then cause the cable 11 to be drawn in upon the drum 25 or released from

said drum to raise or lower the individual extension 2. When the proper position of this extension has been secured the lever 32 will be pressed forward to engage the dogs 28 with the dogs 29. The adjustment successively of each of the staging units having been completed, the raising or lowering of the entire series of staging units will be accomplished in the following manner. Cable 40 having been wound successively upon each of the drums 26 throughout the series, will, after the initial setting of the various staging units be drawn taut to restrain the rotation of shafts 27 throughout the series and will, therefore, be supporting the weight of the staging planks 7 throughout the entire staging construction. If these planks and the other staging equipment secured to the extension 2 are desired to be raised or lowered, a single manual rotation of the drum of the staging unit at the extreme left of the series will cause the cable 40 to be wound upon or unwound from the drum 26 of said unit and will in turn cause rotation of each of the drums 26 throughout the series with the result that the drums 25 connected therewith through the clutch dogs 28 and 29 will rotate and simultaneously raise or lower each of the extensions 2 in the series.

It is understood of course that the rack and pawl mechanism operatively connected with each of the drums 26 throughout the series will have been automatically disengaged by the links 37 and 38 when the shaft 27 was thrust rearwardly and the drums 25 and 26 were forced into engagement. The entire control of the series is concentrated at the extreme left end of the series where the rack and pawl are virtually sustaining the weight of the entire extensible portion of the staging. Manual control of the one rack and pawl is easily accomplished and the single cranking operation completes the change in height of all the extensible units.

I claim:

1. A staging comprising a main ladder and an extension ladder section and a drum rotatably supported by the main ladder section, a pulley on the main ladder section, and spaced from the drum and a cable wound upon the drum and operable over the pulley for control of the extension ladder section and a second cable wound upon the drum for remote control of rotation thereof.

2. A staging comprising spaced extensible units including extensible parts and a main drum and a cable for independent operation of each extensible part, an auxiliary drum for each unit, a clutch for interconnecting each main and auxiliary drum, a key for normally holding said clutch in operative position, a rack and pawl for control of said auxiliary drum, motion transmitting connections between the clutch and said pawl

whereby movement of the clutch to operative position will cause the pawl to engage said rack.

3. A ladder, including a base section and an extensible section, a frame mounted upon the base section, a main drum and an auxiliary drum mounted for independent rotation on the frame, clutch members for said drums, whereby to alternatively provide for dependent or independent rotation of the drums, cable connection between the main drum and the extensible section, whereby to control extension thereof by rotation of the main drum, and a cable connection with the auxiliary drum, whereby to control rotation thereof from a point remote from the base section.

4. A ladder, including a base section and an extensible section, a frame mounted upon the base section, a main drum and an auxiliary drum mounted for independent rotation on the frame, clutch members for said drums, whereby to alternatively provide for dependent or independent rotation of the drums, cable connection between the main drum and the extensible section, whereby to control extension thereof by rotation of the main drum, a cable connection with the auxiliary drum, whereby to control rotation thereof from a point remote from the base section, and a ratchet and pawl for controlling rotation of the auxiliary drum and the main drum when the clutch is engaged for co-operative rotation thereof.

5. A staging unit including a base section and an extensible section, a frame mounted on the base section, a main drum and auxiliary drum mounted on the frame for independent rotation, cable connection between the main drum and the extensible section to control extension thereof, cable connection with the auxiliary drum whereby to control rotation thereof from a point remote from the base section, a ratchet and pawl for controlling rotation of the auxiliary drum, a clutch for interconnecting the auxiliary drum with the main drum for simultaneous rotation thereof and a connection between the clutch actuating mechanism and the pawl whereby to position the pawl in inoperative relation to the ratchet when the drums are interconnected for simultaneous rotation.

6. A staging including a plurality of like units each provided with a base section and an extensible section, a frame for each base section, a main drum and an auxiliary drum for each frame, cable connection between the main drum of each base section and its co-operating extensible section, whereby to control the degree of extension of said extensible section, cable connection between the auxiliary drums of the various base sections, whereby to simultaneously rotate all of the auxiliary drums, a clutch for alternatively co-

ordinating the rotation of the auxiliary and main drums of each base section and a crank connected with each main drum for manual rotation thereof.

- 5 7. A multiple unit staging, including a plurality of extensible units provided with base sections and extensible sections, a frame for each base section, a main shaft for each frame, a main drum mounted upon said shaft
- 10 for rotation therewith, an auxiliary drum mounted for rotation upon said shaft, clutch dogs for each of said drums adapted to interlock to cause simultaneous rotation of the

drums, a clutch arm for slidably moving one of said drums to cause said clutch dogs to interlock, a ratchet and pawl for controlling rotation of the auxiliary drum, a link between one of the drums and the pawl, whereby to cause the pawl to be disengaged from the ratchet when the clutch dogs are interlocked, cable connection between the auxiliary drums whereby to cause said drums to be simultaneously rotated and cable connection between the main drum and the extensible unit associated therewith.

15 20 MIKE KIRSCH.
